UNITED STATES PATENT OFFICE.

GEORGE DURRANT, OF GORTON, ENGLAND.

APPARATUS FOR STRAIGHTENING WEFT IN FABRICS.

Application filed March 16, 1928, Serial No. 262,263, and in Great Britain April 19, 1927.

This invention relates to apparatus for straightening the weft in fabrics as such are being fed to mangles, drying, stentering and other machines after the fabrics have undergone other operations in which there has been a tendency to cause tight and slack selvages, as often occurs, for instance, in bleaching operations where the fabric is traversed considerable distances through porcelain eyes at varying degrees of tension. By "straightening the weft" is meant, so operating on the fabric being fed to one or other of the machines referred to, as to bring the weft from a diagonal, arched, bowed or other irregular position to a position as near as possible at right angles to the selvages.

The object of the invention is a new or improved construction of apparatus for effecting the desired straightening of the weft in fabrics.

According to the invention, the improved apparatus comprises a long cylinder made up of a plurality of short cylinders arranged end to end upon a common shaft and all normally free to be driven or rotated by the fabric, braking means being provided for varying the peripheral speed of any of the short cylinders according to the required correction of the weft.

The fabric to be treated is passed over the composite cylinder prior to entering the mangle, stentering or other machine, and owing to its tension, the fabric presses frictionally upon the cylinders and rotates them about their shaft, provided they are free. If the weft is not distorted, the cylinders are allowed to remain free, but should the weft be distorted, one or more of the cylinders is, or are, held against rotation, or their rotation checked, by the brakes, with the result that one part of the width of the fabric can travel forward freely, while another part or parts is or are retarded, thereby, in the case of say the weft lying diagonal to the width of the fabric, moving forward one end of the weft and retarding the other end until the whole weft lies at right angles to the selvages, when the cylinders (previously held stationary or checked) are made free and allowed to remain free until the weft again requires to be straightened.

In one example of the improved apparatus, a shaft is provided mounted at each end in suitable fixed bearings or supports. Upon such shafts are freely mounted end to end,

a number of comparatively short cylinders, each slightly reduced in diameter at one end and the several cylinders collectively extending to the full width of the fabric.

The larger diameter of each cylinder is 60 covered with rubber, felt, cloth or other suitable frictional material. The smaller diameter of each cylinder will be plain (uncovered), and the surface of the cylinder itself form the braking surface, but, if desired, it 65 also may be covered with a frictional material.

At a point below the reduced part of each cylinder is a pivoted brake shoe, and controlling such brake shoe, through suitable intermediate gear, is a hand lever. Such intermediate gear may be a wedge-shaped bar lying between two rollers, one of which is carried by a pivoted link-like member on which the brake shoe rests and the other of which 75 is carried by a stationary support.

To protect the fabric from the brake surfaces, and also to provide, as near as possible, a continuous or flush cylindrical surface for the fabrics to pass over, there may be a segmental strap or band of metal or other suitable material lying around the reduced part of each cylinder, each strap or band being supported by a ring-like bearer mounted loosely on the cylinder shaft and secured at 85 its lower part to a fixed part of the machine. The ring-like bearers also help to support the shaft about which the cylinders rotate.

Upon the accompanying drawing:

Fig. 1 is a front elevation, and

Fig. 2 an end elevation of weft-straightening apparatus constructed according to the invention.

Fig. 3 is an enlarged front elevation, and

Fig. 4 is an enlarged side sectional elevation 95 of detail parts hereinafter described.

Fig. 5 is an enlarged front elevation of one of the short cylinders which collectively form the composite cylinder.

Referring to the drawings, 'a, a' are the 100 short cylinders, there being seven in the example shown. 'b' is the reduced part or brake surface of each short cylinder drum. The part of larger diameter is covered with a close-fitting sheath of frictional material (see Fig. 105 5).

'c' is the shaft upon which the cylinders are mounted, such shaft being supported in fixed bearings 'd, d', and being held stationary while the cylinders 'a, a' are all normally free to 110

rotate about said shaft. Anti-friction bearings may be provided, if desired.

5 *e, e* are the segmental brake shoes, one for each short cylinder and each pivotally connected to a bracket *f*, mounted on a cross-beam *g* of the machine frame. Each brake shoe acts upon the lower part of the cylinder only.

10 To fill in the gap that would otherwise be left between the shoulder of one short cylinder and the end of the next, and also to provide a continuous or approximately continuous or flush surface for the fabric to lie against, a strip of polished or smooth brass or 15 other suitable material *h* is provided, such strip completely encircling the part *b* of the cylinder except where the brake shoe comes, see Figs. 3 and 4. Each strip *h* is supported by a disc ring *i*, loosely mounted on the shaft 20 *c* and held against rotation and, in part, supported by a rod *i* connected to the beam *g*.

25 The smooth face of the strip *h* offers little or no resistance to the fabric, while the surfaces of the cylinders afford a frictional resistance, and thereby cause the cylinders normally to rotate with the fabric as it passes over them.

30 To each brake shoe is fitted a short set-stud *j*, the inverted "head" of which bears against the top face of a member *k*, pivoted to the bracket *f*. Carried by said member *k*, and by a fixed bracket *l*, are rollers *m¹*, *m²*, one situated directly over the other. Between the rollers extends the wedge-shaped end of a bar *n*. At its other end said bar is pivoted to the 35 lower end of a hand lever *o*, see Fig. 2, said lower end of the hand lever projecting between fixed cross-rails *p* and *p¹*, and abutting against the edge of the rail *p* (as shown) when the lever is pulled to its furthest forward 40 position. In such position, the brake shoe has its fullest braking effect on its pulley *a*, whilst by moving the lever handle forward and drawing back the bar *n* from between the rollers *m¹*, *m²*, the braking effect is reduced 45 in proportion.

50 The fabric requiring to be guided into a mangle, drying, stentering or other machine, and to have its weft corrected, is first threaded below a guide roller *t*, then against a pair of independent pendulous cones *r*, *r* carried by spring-influenced swing arms *s*, *s*, then over the cylinders *a*, *a*, and finally below a further guide roller *q*.

55 Normally, the hand levers *o* will be pushed forward and the brake shoes allowed to lie clear of the cylinders. As the fabric passes over them, the cylinders are rotated at the same speed and have no effect on the fabric. When, however, the weft is other than at 60 right angles to the selvages, say one part lying in advance of another part, the cylinder below such advanced part is retarded by the attendant raising its brake shoe, and checking the further rotation of the cylinder, until 65 all the weft is again in line, when the cylinder

is released and allowed to revolve freely with the other cylinders. The attendant will usually pull over the hand levers, one by one (or two by two) at any point in the width of the fabric, releasing them and checking them 70 individually (or in series) as may be necessary.

75 While hand-lever control of the brake shoes will usually be sufficient, it will be apparent that the control may be automatic. For such purpose, variations in the tension of the fabric, after passing below the guide roller *q*, or before passing over the pulleys *a*, *a*, may be used to move levers, which, in turn, will operate the brake shoes, any undue slackening (or 80 tightening) of one part of the fabric causing the levers to move in (or out) and thus check or release the cylinders.

85 The cones *r*, *r* by being independent of one another, take up any uneven tension in the fabric.

What I claim is:—

90 1. Apparatus for straightening weft in fabrics, characterized by a relatively long cylinder made up of a plurality of short cylinders arranged end to end and all of which are normally free to be driven or rotated by the fabric, by braking means for varying the peripheral speed of any of the short cylinders according to the required correction of the weft, and by guide cones axially and pivotally mounted in the path of the fabric on the inlet side of the machine, and springs for holding the cones yieldingly against the fabric to tension same, as set 100 forth.

95 2. In apparatus for straightening weft in fabrics, a plurality of relatively short friction cylinders, each formed with a reduced part at one end, a shaft upon which said cylinders are mounted end to end and upon which they are normally free to rotate, a brake shoe for each cylinder adapted to contact with the reduced part, or to lie clear of same, and means for controlling the brake 110 shoes individually, as set forth.

115 3. In weft straightening apparatus as claimed in claim 2, a pivoted brake shoe for each cylinder, a set-stud and a pivoted member for supporting said shoe, a bar with wedge-shaped end lying between a roller carried by said pivoted member and a further carrier roller carried by a fixed support positioned beneath the first roller and a lever for moving the bar to and fro between the 120 rollers, as set forth.

125 4. In apparatus for straightening weft in fabrics, a plurality of relatively short friction cylinders collectively forming a single long composite cylinder, equal approximately to the width of the fabric, each cylinder having a part with reduced diameter at one end, a long stationary shaft upon which said cylinders are mounted, anti-friction bearings for each cylinder, a brake shoe for each 130

cylinder, means for supporting the brake shoe to cause it to contact with the cylinder or lie clear of same, a stationary ring adjacent the part with reduced diameter of each cylinder, and a strip of smooth material carried by said ring and surrounding the reduced part of the cylinder except where the brake shoe comes, as set forth.

5. In apparatus for straightening weft in fabrics, a plurality of relatively short friction cylinders, each formed with a reduced part at one end, a shaft upon which said cylinders are mounted end to end and upon

which they are normally free to rotate, a brake shoe for each cylinder adapted to contact with the reduced part, or to lie clear of same, and means for controlling the brake shoes individually, a pair of independent guide cones, springs for exerting a pull on the cones, and guide rollers for the fabric to pass over on its way to and from the cylinders, as set forth. ¹⁵

In testimony whereof I have signed my name to this specification.

GEORGE DURRANT.
